ROADSIDE RESTAURANT

Anthony J. Rupolo, 118 Pine Neck Ave., Patchogue, N.Y.

Filed June 17, 1963, Ser. No. 75,371

Term of patent 14 years

(Cl. D13—1)

Fig.1.

Fig.4.

Fig.2.

Fig.3.

FIG. 2 is a side view;

FIG. 3 is a rear view; and

FIG. 4 is a front view.

The side of the restaurant opposite that shown in FIGURE 2 is substantially the same in appearance as the side shown in FIG. 2.

I claim:

The ornamental design of a roadside restaurant, as shown and described.
